UNITED STATES PATENT OFFICE

91,007

DESIGN FOR A SHOE

Benjamin F. Bernstein, Haverhill, Mass., assignor to Sterling Shoe Corporation, Haverhill, Mass., a corporation of Massachusetts

Application July 27, 1933. Serial No. 48,855

Term of patent 3½ years

To all whom it may concern:

Be it known that I, BENJAMIN F. BERNSTEIN, a citizen of the United States and a resident of Haverhill, county of Essex and Commonwealth of Massachusetts, have invented a new, original, and ornamental Design for a Shoe, of which the following is a specification, reference being had to the accompanying drawing, in which Fig. 1 is a side elevation of a shoe showing my new design, the dominant feature of the design residing in the ornamentation on the vamp of the shoe; and Fig. 2 is a plan thereof.

I claim:

The ornamental design for a shoe substantially as shown and described.

BENJAMIN F. BERNSTEIN.
